UNITED STATES PATENT OFFICE.

CHARLES PREW, OF FALL RIVER, MASSACHUSETTS.

FLIER.

Application filed November 28, 1921. Serial No. 518,297.

To all whom it may concern:

Be it known that I, CHARLES PREW, a citizen of the United States, residing at Fall River, in the county of Bristol, and State 5 of Massachusetts, have invented new and useful Improvements in Fliers, of which the following is a specification.

This invention has for its primary object the provision of a presser for the fliers of 10 roving machines, the presser being equipped with a wind blade which tends to force the finger of the presser through the roving while in action to eliminate breaking during each set of roving, with a resultant in- 15 crease in production.

Another object of the invention resides in providing a presser of the above mentioned character which is designed to be quickly and easily associated with fliers of general 20 construction, and upon being fixed thereto requires no adjustment thereafter.

The nature and advantages of the invention will be better understood when the following detailed description is read in connection 25 with the accompanying drawing, the invention residing in the construction, combination and arrangement of parts as claimed.

In the drawing forming part of this application, like numerals of reference indicate similar parts in the several views and wherein:—

Figure 1 is a view in elevation, showing the attachment associated with the flier of 35 a roving machine.

Figure 2 is a sectional view taken on line 2—2 of Figure 1.

Figure 3 is a detail view of the presser.

Referring to the drawing in detail, 10 indicates a flier of well-known construction which is associated with the spindle 11 of a roving machine, the spindle having mounted thereon a bobbin indicated at 12. A substantially U-shaped presser finger is indicated at 14 and is arranged in parallelism with one arm of the flier with which it is associated. Projecting at right-angles from the lower end of the presser and thence being curved toward the bobbin there is an extension 14' which carries the usual shoe 15 which is susceptible of movement toward or away from the longitudinal axis of the bobbin and controlled in a manner to be presently described. The presser is formed 50 with loops 16 adjacent its respective ends and which embrace the adjacent limb of the

flier in a manner to permit of partial rotation of the presser in either direction. Integrally formed on the upper end of the presser 14 is an axe shaped wind blade 17 which projects from the presser inwardly of the flier, the disposition of this blade being such as to tend to force the shoe of the presser toward the roving while in action thus lessening the number of ends breaking during each set of roving which results in increased production. The construction is such that it will also enable the roving frames to operate at a higher speed on the spindle. The number of turns of the material generally put round the finger of the presser now in use, is two and one-half turns, while with the presser constructed in accordance with my invention, one and one-half turns round the finger can be run successfully, therefore lessening the strain of the material while being wound into roving. By reason of this fact, the roving can be made with less twist of the material.

While it is believed that from the foregoing description, the nature and advantages of the invention will be readily apparent, I desire to have it understood that I do not limit myself to what is herein shown and described, and that such changes may be resorted to when desired as fall 85 within the scope of what is claimed.

What I claim is:

The combination with a flier for a roving, of a presser finger of the character described comprising a body portion arranged in close proximity and in parallelism with one arm of the flier, a shoe extension extending at right angles from the lower end of the body portion and thence being curved upon itself, a loop formed on said finger at the juncture of the extension and the body portion and adapted to surround the end of the arm, an axe shaped wind blade integrally formed on the upper end of the body portion and projecting inwardly from the flier in the manner described and a second loop formed on the finger at the juncture of the body portion and the blade for associating the finger with the arm together with the first mentioned loop in a manner to permit the partial rotation thereof in either direction for the purpose specified.

In testimony whereof I affix my signature.

CHARLES PREW.
